UNITED STATES PATENT OFFICE.

FRANK A. JILLSON, OF RACINE, WISCONSIN.

INDICATOR-LOCK.

SPECIFICATION forming part of Letters Patent No. 299,395, dated May 27, 1884.

Application filed March 4, 1884. (No model.)

To all whom it may concern:

Be it known that I, FRANK A. JILLSON, of Racine, in the county of Racine, and in the State of Wisconsin, have invented certain new and useful Improvements in Indicator-Locks; and I do hereby declare that the following is a full, clear, and exact description thereof.

My invention relates to indicator-locks, and will be fully described hereinafter.

10 In the drawings, Figure 1 is a plan view of my lock. Fig. 2 is a side view. Fig. 3 is a plan view of the under side of the lid. Fig. 4 is a longitudinal section. Fig. 5 is a plan of my lock with lid removed. Fig. 6 is a like 15 view with dials removed. Fig. 7 is a section through line xx , Fig. 1. Fig. 8 shows details. Fig. 9 is a view of part of a car with a modified form of my lock in place thereon. Fig. 10 is a view showing the locking end of the 20 same closed, and Fig. 11 a view showing it open. Fig. 12 is a like view of the lock turned over.

The case of my improved lock is made in two parts, A A', the part A forming what I 25 call the "bottom" of the case, while A' is the lid or cover. The bottom is provided with studs a a' &c. On the stud a , I first slip a ratchet-wheel, B, having a hub that projects up to receive a wheel, B', that has a single 30 rounded tooth, b , projecting out from its periphery, and above this a dial-plate, B². The next stud, a' , carries a dial-plate, B³, a single-tooth wheel, C, and a cog-wheel, C'. Stud a' carries merely a dial-plate and cog-wheel. 35 The ratchet-wheel B lies near the bottom A' of the case, in position to receive a pawl, E, that is hinged to a slide, E', and this slide has a bifurcated lug, E², that grasps loosely the trunnion of a latch, F, so that the latch may 40 be fully turned over onto the case or off of it independently of the slide; but the latch cannot be moved in the direction of the length of the trunnion without carrying the slide with it. The slide E' has a shoulder, E³, that projects through a slot in the edge of the case, and the case is provided with a flange, e, that is slotted or bored vertically to take a sealing-wire, e'. The shoulder E³ of the slide is correspondingly perforated to receive the sealing-wire, and also has an opening to take a padlock, E⁴, which, by abutting against the flanges e of the case, will prevent the slide from re-

ciprocating. After the two parts of the case have been placed together, the case is secured to the door by a bolt, f, at the rear, and the 55 shank of a staple, F', in front, the staple projecting above the top plate, A', far enough to take the hasp F² and permit the tongue F³ of latch F to pass in over the hasp to lock it in place; and to retain the latch F in this position 60 when the padlock is not in use, I provide the latch with a notched lug, g, and provide a catch, g', that reciprocates at right angles to the case, and place a spring, g², behind it, that serves to force it into the notch in lug g when 65 the latch is in the position shown in Fig. 5, this latch to be withdrawn when required by pressure on the handle g³. A spring, c, bearing on the head of pawl E, serves to hold it in position to engage with the teeth of wheel B, 70 so that whenever the latch F is drawn back far enough to carry its tongue F³ out of the staple the pawl will jig the wheel B one tooth, and then if the latch is thrust forward again to again lock the hasp in place the next time it is 75 withdrawn another jiggling will take place, each jiggling causing a new number to appear at opening 1 in top of the case, and thus each time the latch is thrown over and forward the wheel B will be jiggled one tooth, carrying the 80 wheel B' about with it until tooth b comes into mesh with wheel C'. When this occurs, the tooth b will jig the wheel C' one space, and as its dial-plate turns with it will cause it (dial-plate B²) to expose a new figure, and then the 85 tooth b, when next the slide E' is reciprocated, will pass out of mesh with wheel C', and for the next nine reciprocations of the slide E' the wheels B B' will be jiggled independently of wheel C', causing the dial-plate B² to expose a 90 different figure at each jiggling, each complete revolution bringing the tooth b into position for jiggling wheel C' one space, and each entire revolution of wheel carrying the wheel Cabout, so that its tooth b will jig the wheel C' on stud 95 a', which in turn at each successive revolution jigs the wheel C' on stud a³ one space, so as to cause its dial to show a new letter or figure, and thus every time the lock is opened a new combination of letters or figures is displayed, 100 as in Fig. 1.

It will be observed that the crown of each tooth of the cog-wheels C' is concaved to conform to the periphery of wheel C, and therefore

each cog-wheel is locked by its adjacent wheel C until the tooth b reaches it.

In the modifications shown in Figs. 9, 10, 5 11, and 12, I have a different form of latch and means of connecting it with the slide E', the slide E' being made of a general U shape, the band of the slide having ears h, in which the latch F is hinged, this change dispensing entirely with the trunnion of the latch shown 10 in Figs. 5 and 6. The shorter arm of the slide is formed with a catch for engagement with another catch, g', also of modified form. In both instances I provide a safety-pawl, c', that is actuated by a spring, C', to aid in holding 15 the wheel B. The rear end of pawl E is also provided with a dog, E'', that also performs the same office when the slide is in the position shown in Fig. 10. Therefore it will be absolutely impossible to turn the wheel B 20 without drawing out slide E'.

Having thus fully described my invention, what I claim as new, and desire to secure by Letters Patent, is—

1. A many-toothed wheel, B, and dial B', in combination with a single-toothed wheel 25 adapted to turn with said many-toothed wheel and dial, an interdental wheel, and another dial, the two latter revolving together, whereby the latter is jiggled once at each revolution of wheel, the teeth of which have crowns that 30 are concaved to conform to the periphery of the single-toothed wheel B', as described.

2. The wheel B, having raised teeth, in combination with the slide and its pawl, the latter having a rear dog, E'', to aid the head of 35 the pawl in locking the wheel B and preventing it from being turned except through the slide, as set forth.

In testimony that I claim the foregoing I have hereunto set my hand, at Milwaukee, in 40 the county of Milwaukee and State of Wisconsin, in the presence of two witnesses.

FRANK A. JILLSON.
